(57) **ABSTRACT**

A protective helmet having a protective shell, a low friction layer, and a comfort liner is disclosed. The protective shell includes an energy absorbing material and an inner surface. The low friction layer is coupled to the inner surface of the protective shell. The low friction layer may be plastic having a thickness of less than approximately 3 mm. The comfort liner is removably coupled to the low friction layer opposite the protective shell, and includes a low friction material, such as brushed nylon, adjacent the low friction liner. The comfort liner may be removably coupled protective shell with either clips that removably couple to receivers embedded in the brow of the helmet, with elastically deformable couplings that extend from the comfort liner to the protective shell, or both.

PROTECTIVE HELMET

CROSS REFERENCE TO RELATED APPLICATIONS

This document claims the benefit of the filing date of U.S. Utility application Ser. No. 14/925,874, filed Oct. 28, 2015 and Provisional Patent Application 62/069,679, filed on Oct. 28, 2014, both of which are incorporated herein by reference.

FIELD OF DISCLOSURE

Aspects of this document relate generally to protective helmets.

BACKGROUND

Conventional helmet system include comfort liners adjacent a protective shell of the helmet. While the comfort liner may improve comfort the wearer, the rotational movement of the comfort liner with respect to the protective shell is limited during impact due to the friction between the comfort liner and the protective shell.

SUMMARY

According to one aspect, a protective helmet comprises a protective shell, a low friction layer, and a comfort liner. The protective shell comprises an energy absorbing material and an inner surface. The low friction layer is coupled to the inner surface of the protective shell. The comfort liner is removably coupled to the low friction layer opposite the protective shell, and comprises a low friction material adjacent the low friction liner.

Various implementations and embodiments may comprise one or more of the following. The low friction material of the comfort liner may comprise brushed nylon. The low friction layer may comprise a plastic low friction layer comprising a thickness less than approximately 3 mm. The comfort liner may be removably coupled to the protective shell with one or more elastically deformable couplings that extend from the comfort liner through the low friction layer to the protective shell. The protective shell may comprise a receiver on a lower edge of the protective shell, the receiver extending into the protective shell from the lower edge of the protective shell, and the comfort liner may comprise a clip removably coupled within the receiver to couple the comfort liner to the protective shell with the low friction layer positioned between the protective shell and the comfort liner. A neck roll pad coupled to the comfort liner with a four-way stretch fabric.

According to another aspect, a protective helmet comprises a protective shell, a low friction layer and a comfort liner. The protective shell comprises an energy absorbing material and an inner surface. The low friction layer is coupled to the inner surface of the protective shell. The comfort liner is removably coupled to the low friction layer opposite the protective shell with one or more elastically deformable couplings that extend from the comfort liner through the low friction layer to the protective shell.

Various implementations and embodiments may comprise one or more of the following. The low friction layer may comprise a plastic low friction layer having a thickness of approximately 3 mm or less. The comfort liner may comprise a low friction material adjacent the low friction layer. The low friction material of the comfort liner may comprise

brushed nylon. The protective shell may comprise a receiver on a lower edge of the protective shell, the receiver extending into the protective shell from the lower edge of the protective shell, and the comfort liner may comprise a clip removably coupled within the receiver to couple the comfort liner to the protective shell with the low friction layer positioned between the protective shell and the comfort liner. A neck roll pad coupled to the comfort liner with a four-way stretch fabric.

According to another aspect, a protective helmet comprises a protective shell and a comfort liner. The protective shell comprises an energy absorbing material, an inner surface, and a receiver on a lower edge of the protective shell, the receiver extending into the protective shell from the lower edge of the protective shell. The comfort liner is removably coupled to the inner surface of protective shell, and comprises a clip removably coupled within the receiver to removably couple the comfort liner to the protective shell.

Various implementations and embodiments may further comprise one or more of the following. The receiver may comprise a U-shaped slot extending inward into the protective shell from the bottom edge and a plurality of tabs extending inward within the U-shaped slot. A low friction layer coupled to the inner surface of the protective shell between the comfort liner and the protective shell. The low friction layer may comprise a plastic low friction layer having a thickness of approximately 3 mm or less. The comfort liner may comprise a low friction material adjacent the low friction layer. The low friction material comprises brushed nylon. The comfort liner may be removably coupled to the protective shell with one or more elastically deformable couplings that extend from the comfort liner through the low friction layer to the protective shell. A neck roll pad coupled to the comfort liner with a four-way stretch fabric.

The foregoing and other aspects, features, and advantages will be apparent to those artisans of ordinary skill in the art from the DESCRIPTION and DRAWINGS, and from the CLAIMS.

BRIEF DESCRIPTION OF THE DRAWINGS

The invention will hereinafter be described in conjunction with the appended drawings, where like designations denote like elements, and:

FIG. 1 is a top perspective view of a first embodiment of a protective helmet;

FIG. 2 is a bottom perspective view of a first embodiment of a protective helmet;

FIG. 3 is a bottom view of a brow of a first embodiment of a protective helmet with a clip of a comfort liner coupled to a receiver on the protective shell;

FIG. 4 is a bottom view of a brow of a first embodiment of a protective helmet with a clip of a comfort liner detached from a receiver on the protective shell;

FIG. 5 is a bottom view of a second embodiment of a protective helmet;

FIG. 6 is a side view of a first embodiment of a comfort liner; and

FIG. 7 is a bottom view of a second embodiment of a comfort liner.

DETAILED DESCRIPTION

Protective head gear and helmets have been used in a wide variety of applications and across a number of industries including sports, athletics, construction, mining, military defense, and others, to prevent damage to a users head and

brain. Damage and injury to a user can be prevented or reduced by preventing hard objects or sharp objects from directly contacting the user's head, and also from absorbing, distributing, or otherwise managing energy of the impact.

This disclosure, its aspects and implementations, are not limited to the specific material types, components, methods, or other examples disclosed herein. Many additional material types, components, methods, and procedures known in the art are contemplated for use with particular implementations from this disclosure. Accordingly, for example, although particular implementations are disclosed, such implementations and implementing components may comprise any components, models, types, materials, versions, quantities, and/or the like as is known in the art for such systems and implementing components, consistent with the intended operation.

The words "exemplary," "example," or various forms thereof are used herein to mean serving as an example, instance, or illustration. Any aspect or design described herein as "exemplary" or as an "example" is not necessarily to be construed as preferred or advantageous over other aspects or designs. Furthermore, examples are provided solely for purposes of clarity and understanding and are not meant to limit or restrict the disclosed subject matter or relevant portions of this disclosure in any manner. It is to be appreciated that a myriad of additional or alternate examples of varying scope could have been presented, but have been omitted for purposes of brevity.

While this disclosure includes embodiments of many different forms, there is shown in the drawings and will herein be described in detail particular embodiments with the understanding that the present disclosure is to be considered as an exemplification of the principles of the disclosed methods and systems, and is not intended to limit the broad aspect of the disclosed concepts to the embodiments illustrated.

Accordingly, this disclosure discloses protective headgear, as well as a system and method for providing a helmet or protective headgear, that can be used for a cyclist, football player, hockey player, baseball player, lacrosse player, polo player, climber, auto racer, motorcycle rider, motocross racer, skier, snowboarder or other snow or water athlete, sky diver or any other athlete, recreational or professional, in a sport. Other non-athlete users such as workers involved in industry, including without limitation construction workers or other workers or persons in dangerous work environments can also benefit from the protective headgear described herein, as well as the system and method for providing the protective head gear.

Various implementations and embodiments of protective helmets according to this disclosure comprise a protective shell **10**. The protective shell **10** can be made of an energy absorbing material, such as expanded polystyrene (EPS), expanded polyurethane (EPU), expanded polyolefin (EPO), expanded polypropylene (EPP), or other suitable energy managing material. The energy absorbing material can be part of a hard-shell helmet such as a skate bucket helmets, motorcycle helmets, snow sport helmets, football helmets, batting helmets, catcher's helmets, or hockey helmets. As shown in FIGS. 2-4, the disclosed protective helmets include an additional outer protective shell **3** disposed outside, or over, the protective shell **10**. In other words, FIGS. 2-4 show an outer shell **3** that is disposed outside of, or over, the energy absorbing material. In hard shell applications, the energy absorbing material can comprise one or more layers of EPP and provide more flexibility than available with conventional in-molded helmets. Alternatively, the energy

absorbing material can be part of an in-molded helmet such as bicycle helmet or cycling helmet. Because bicycle helmets typically include openings in the energy absorbing material for ventilation to airflow can through the helmet and cooling of a wearer's head, cycling applications could require modified low friction layers. As an energy-absorbing layer in an in-molded helmet, the protective shell **10** can comprise rigid materials such as EPS and EPU. The additional outer shell layer **3**, such as a layer of stamped 10 polyethylene terephthalate (PET) or a polycarbonate shell, can be included on an outer surface of the protective shell **10** of the helmet and be bonded directly to the expanding foam (e.g. PET layer added to the EPS as it is expanding such that the foam is molded in the shell). In other words, the 15 additional outer shell **3** that is directly connected to the energy absorbing material is shown in FIGS. 2-4.

FIGS. 1-4 depict a non-limiting embodiment of a protective helmet **2** according to this disclosure. In one or more embodiments, a protective shell **10** comprises a plurality of 20 layers of energy absorbing material coupled to one another. For example, in the non-limiting embodiment of a protective helmet **2** shown in FIGS. 3 and 4, the protective shell **10** comprises a first layer **11**, a second layer **12**, and a third layer **13** of energy absorbing material coupled to one another to 25 form a protective shell **10**. As shown in FIGS. 2-4, the outer surface of the first layer **11** of the energy absorbing material is positioned adjacent to and is connected to the inner surface of the additional outer shell **3**. In embodiments comprising a plurality of layers of energy absorbing material 30 coupled to one another, the inner surface of the protective shell **10** is the inner surface of the innermost layer of energy absorbing material. For example, in the non-limiting embodiment shown in FIGS. 3 and 4, the inner surface of the protective shell **10** is the inner surface of the third layer **13** of energy absorbing material (not visible in FIGS. 3 and 4), the inner surface of the third layer **13** of energy absorbing material being directed to or facing the head of the wearer when the protective helmet **2** is worn. In other embodiments, such as the non-limiting embodiment of a protective helmet 35 **4** depicted in FIG. 5, a protective shell **8** may comprise a single layer of energy absorbing material. In such an embodiment, the inner surface **9** is also directed to or facing the head of the wearer when the protective helmet **4** is worn. Embodiments of a protective shell may also include an outer 40 surface formed opposite the inner surface that may be oriented away from the wearer's head.

Various implementations and embodiments of protective helmets contemplated in this disclosure may further comprise a low friction layer **30** (shown in FIG. 5) coupled to an 45 inner surface **9** of a protective helmet. Although a low friction layer **30** is not visible in the non-limiting embodiment shown in FIGS. 1-4, one or ordinary skill in the art will understand how the low friction layer **30** shown coupled to a protective helmet **4** in FIG. 5 may be applied to other 50 protective helmets. The non-limiting example of a low friction layer **30** in FIG. 5 is formed of a transparent plastic. Although reference is made below to the inner surface **9** of the protective shell **8** of the protective helmet **4** shown in FIG. 5, it is contemplated that a low friction layer **30** having 55 similar features may be applied to the protective helmet **2** shown in FIGS. 1-4. By forming a thin low friction layer **30**, such as is described herein, the low friction layer **30** may provide for rotational energy management without requiring additional thick or bulky layers between the outer surface of 60 the helmet and the wearer's head. As such, embodiments of providing rotational energy management contemplated as 65 part of this disclosure may be implemented with conven-

tional helmet designs, sizes, and dimensions, without interfering with helmet fit, or requiring helmet redesigns to accommodate improvements for rotational energy management.

According to some aspects, a low friction layer **30** may be formed of plastic, such as PET or polycarbonate, as well as other materials such as carbon fiber, fiberglass, or any other suitable material that provides a low friction inner surface that is oriented towards the head of a wearer and positioned to interface a comfort liner (described in greater detail below). In one or more embodiments, a low friction layer **30** comprises a contoured surface that follows a contour, topography, or shape of the inner surface **9** of the protective shell **8**. A topography, shape, or geometry of the low friction layer **30** may also account for helmet ventilation. According to some aspects, a low friction layer **30**, whether contoured or not contoured, comprises a thickness in a range of 0-3 mm, or a thickness less than 1 mm. A low friction layer **30** may also include projections, tabs, or pegs that can be perpendicular with, or extend away from, the contoured surface of the low friction layer **30** and be imbedded within the protective shell **8** to secure the low friction layer **30** to the protective shell **8**, as shown in FIG. 5. A low friction layer **30** may be coupled to the inner surface **9** of a protective shell **8**, especially for in-molded helmets, as a plastic shell formed of in-molded polycarbonate, PET, or other suitable plastic in a way that is the same or similar to a way in which outer plastic shells **3** can be coupled to in-molded helmets. A low friction layer **30** may also be coupled to the protective shell **8** after the protective shell **8** is fully formed. In some instances, a protective shell **8** is added or retrofitted to an existing helmet as part of an after-purchase or after market upgrade to increase protection and management of energy through rotational movement.

Various implementations and embodiments of a protective helmet according to this disclosure may further comprise a comfort liner coupled to the protective shell of the helmet. In some embodiments, a comfort liner is removably coupled to a protective shell of a helmet with the low friction layer positioned between the comfort liner and the protective shell. Various embodiment of comfort liners according to this disclosure may be removably coupled to a protective shell with multiple embodiments of couplings, which shall be described in greater detail below. When coupled to a protective shell, a comfort liner may be disposed within the protective shell of helmet and oriented towards the inner surface of the protective shell of the helmet to provide additional cushion and padding to a wearer's head, while also minimizing, reducing, and filling-in gaps or offsets that might exists between the wearer's head and the protective shell.

FIG. 6 depicts a non-limiting embodiment of a comfort liner **40** according to this disclosure. In one or more embodiments, an outer surface **41** (i.e. the surface that is oriented towards the protective shell of the helmet and away from the wearer's head) comprises exposed padding or raw foam. In other embodiments, a comfort liner **40** comprises an outer surface **41** having a low friction material covering the padding or raw foam. A low friction material may comprise brushed nylon or an equivalent fabric. By including a low friction material such as brushed nylon on an outer surface **41** of the comfort liner **40**, slipping, rotation, and relative movement between the comfort liner **40** and the low friction layer **30** may be promoted or increased such that a wearer's head remains in fixed contact relative to the comfort liner **40** while slipping, rotating, and moving against the low friction liner **30** with respect to the protective shell of the helmet.

A comfort liner **40** according to this disclosure may be formed as unitary or monolithic padded interiors, such as those formed with one-piece sewn basket construction. Unitary construction of the comfort liner allows for reducing or minimizing a number of attachment devices or anchoring points, as discussed in greater detail below. When a comfort liner **40** is disposed adjacent the low friction layer, the comfort liner **40** may be coupled to the protective shell of the helmet with at least one elastically deformable coupling that facilitates rotation and relative movement of the comfort liner **40** with respect to the low friction layer **30**. In the non-limiting embodiment shown in FIG. 6, a comfort liner comprises at least one front elastically deformable coupling **42** and at least one rear elastically deformable coupling **43**. The elastically deformable coupling may be displaced and absorb energy during an impact and then return to an original position after impact.

One or more embodiments of a comfort liner **20**, such as the comfort liner **20** shown in the non-limiting embodiment depicted in FIGS. 3 and 4, comprise one or more straps **24** and one or more attachment devices or clips **25**. Each strap extends between the body of the comfort liner **20** and the attachment device or clip **25**. In the non-limiting embodiment shown in FIGS. 3 and 4, the comfort liner **20** comprises two front straps **24** and two front attachment devices or front clips **25**, wherein each front attachment device or front clip **25** is coupled to a front strap **24**. The front straps **24** and clips **25** are positioned to allow a user to removably couple the attachment devices or clips **25** to a front brow or front lower edge **14** of a protective shell **10** of the helmet **2**. In some embodiments, a comfort liner **20** may comprise one or more rear straps **24** and one or more rear attachment devices or clips **25** similar to that shown in FIGS. 3 and 4 positioned to removably couple the comfort liner **20** to a rear brow or lower edge of a helmet **2**. The straps **24** may be adjustable straps **24** that allow a user to adjust a length of the strap **24**. In particular embodiments, the clips **25** may couple into the front brow of the helmet **2** substantially perpendicularly to the front brow surface. Various embodiments may comprise one or more clips **25** and one or more elastically deformable couplings **42, 43**. For example, a comfort liner **20** may comprise two front clips **25** and two rear elastically deformable couplings **43**. Other embodiments may comprise two front clips **25**, two front elastically deformable couplings **42**, and two rear elastically deformable couplings **43**. Still other embodiments may comprise two rear clips **25** and two front elastically deformable couplings **42**. Other embodiments may comprise any combination thereof.

As noted above, one or more embodiments of a helmet **4** may comprise at least one elastically deformable coupling **42, 43** coupling the comfort liner **40** to the protective shell **8** of the helmet **4**. An elastically deformable coupling **42, 43** may comprise a rubber snap, stopper, or bungees that can be releasably or permanently coupled to the comfort liner **40** and to the protective shell **8**. However, any number or type of suitable attachment devices can be used, as desired, according to the particular needs and application of the helmet. For example, while any number of attachment devices can be used for power sports helmets, some power sports helmets can include four attachment devices (like clips **25**) disposed along a lower edge or perimeter of the comfort liner, as shall be described in greater detail below. For some power sports helmets, a comfort liner **40** or padding can be coupled to the exterior perimeter or lower drip-line of the helmet. Accordingly, the padding can be coupled to the helmet by being sandwiched between an energy absorbing layer (such as EPS) and an outer shell **3**

without any additional attachment devices, such as snaps, because the fit between the outer shell 3 and the energy absorbing layer can function as the attachment device.

For applications involving snow helmets, a sewn basket style pad assembly may be used and coupled to the low friction layer 30 of the protective shell 8. For applications involving bike or cycling helmets, the comfort liner 30 can be coupled to the low friction layer 30 or protective shell 8 as a mesh layer or with openings to accommodate ventilation openings and airflow through the helmet, and a comfort liner comprising plurality of smaller portions or discrete pieces may be used.

In one or more embodiments, an elastically deformable coupling 42, 43 may couple the comfort liner 40 to the protective shell 8 by at least one of the elastically deformable couplings 42, 43 extending through an opening 31, hole, or cut-out of the low friction layer 30. Alternatively, a shape of the low friction layer 30 can be such that the elastically deformable coupling 42, 43 may couple the low friction layer 30 to the protective shell 8 without passing through the low friction layer 30, such as being disposed around a periphery of the low friction layer 30. In yet another embodiment, the elastically deformable coupling may couple the comfort liner 40 directly to the low friction layer 30. In the non-limiting embodiment shown in FIG. 6, each elastically deformable coupling 42, 43 is configured to extend away from the comfort liner 40, through the low friction layer 30 and be coupled directly to the protective shell 8.

As a non-limiting example, an elastically deformable coupling 42, 43 may pass through a circular opening 31 in the clear plastic shell of the low friction layer 30, and snap into a circular opening 7, 6 on the inner surface 9 of the protective shell 8 aligned with the circular opening 31 in the low friction layer 30. Each elastically deformable coupling 42, 43 may thus be coupled at its ends to the protective shell 8 and the comfort liner 40, with a distance or length in-between that allows for elastic movement. Each elastically deformable coupling 42, 43 may be held at its respective ends in the protective shell 8 and comfort layer 40 by a chemical attachment, such as by an adhesive, or by mechanical attachment. Mechanical attachment can include sewing, interlocking, or friction.

In some instances, each elastically deformable coupling 42, 43 comprises an "I" shape with top and bottom widened portions and a narrower central portion. The top widened portion can include a head, tab, or flange, an underside of which contacts the comfort liner 40 around an opening in the comfort liner 40 through which the elastically deformable coupling 42, 43 can pass. The bottom-widened portion can include a head, tab, flange or barbs that contact an inner portion of the opening in the protective shell for receiving the elastically deformable coupling. In any event, the elastically deformable couplings 42, 43 can couple the comfort liner 40 to the protective shell in such a way as to allow a range of motion or relative movement along the low friction layer 30 and with respect to the protective shell 8. The range of motion can be adjusted to a desirable layer amount or distance by adjusting a size, elasticity, or other feature of the elastically deformable couplings.

According to some aspects and as noted above, a comfort liner 20 may be coupled to a protective shell 10 with one or more attachment devices or clips 25. Each attachment device or clip 25 may comprise an elongated attachment device or clip 25 sized to friction or compression fit within a receiver 15 on the protective shell 10 of the helmet 2. In other embodiments, the attachment device or clip 25 may com-

prise a buckle or any other coupling configured to allow a user to removably couple the attachment device or clip 25 to the brow or lower edge 14 of the helmet 2. As noted, various embodiments of a protective helmet 2 comprise one or more receivers 15 embedded within a protective shell 10 of the helmet 2 and positioned to receive an attachment device or clip 25. As shown in FIGS. 2-4, the receivers 15 are positioned between an inner surface 5 of the energy absorbing material and an outer surface of the energy absorbing material. In particular, FIGS. 3 and 4 shown the front receiver positioned near the middle of the energy absorbing material, wherein a majority of the first layer 11 positioned outward of the receiver 15 and the second layer 12 and a third layer 13 are positioned inward of the receiver 15. As used herein, the brow or lower edge 14 of the helmet 2 is the portion of the protective shell 10 just above the eyebrows of the user. The lower edge may also include the edge just above the rear side of the neck of the user. In any event, as used herein, the brow or lower edge 14 of the helmet 2 extends at an angle away from the face or neck of the wearer or from the center of the helmet 2. The lower edge 14, then, comprises a latitudinal edge on the helmet 2 extending outward from the center of the helmet 2. When an attachment device or clip 25 is detachably coupled to receiver 15, the attachment device or clip 25 extends into the receiver 15 substantially perpendicular to the latitudinal lower edge 14 of the protective shell 10. This coupling of the attachment device or clip 25 with the receiver 15 provides a connection that is positioned inward of both the outer shell 3 and the outer surface of the energy absorbing material. In one or more embodiments, the attachment device or clip 25 is substantially perpendicular to a surface upon which the helmet 2 rests (or the ground upon which the wearer stands) when the attachment device or clip 25 is detachably coupled to the receiver 15 embedded within the protective shell 10 of the helmet 2 (assuming the helmet 2 is upright).

Each receiver 15 is configured to removably couple the attachment device or clip 25 to the receiver 15 and thus the protective shell 10 in which the receiver 15 is embedded. Each receiver 15 may comprise one or more teeth 16 configured to pinch a portion of the attachment device or clip 25 and hold the attachment device or clip 25 partially within the receiver 15. Like the elastically deformable couplings 42, 43, the clips 25 and receivers 15 couple the comfort liner 20 to the protective shell 10 in such a way as to allow a range of motion or relative movement along the low friction layer 30 straps 24 and one or more attachment devices or clips 25. Each strap extends between the body of the comfort liner 20 and the attachment device or clip 25. In the non-limiting embodiment shown in FIGS. 3 and 4, the comfort liner 20 comprises two front straps 24 and two front attachment devices or front clips 25, wherein each front attachment device or front clip 25 is coupled to a front strap 24. The front straps 24 and clips 25 are positioned to allow a user to removably couple the attachment devices or clips 25 to a front brow or front lower edge 14 of a protective shell 10 of the helmet 2. In some embodiments, a comfort liner 20 may comprise one or more rear straps 24 and one or more rear attachment devices or clips 25 similar to that shown in FIGS. 3 and 4 positioned to removably couple the comfort liner 20 to a rear brow or lower edge of a helmet 2. The straps 24 may be adjustable straps 24 that allow a user to adjust a length of the strap 24. In particular embodiments, the clips 25 may couple into the front brow of the helmet 2 substantially perpendicularly to the front brow surface. Various embodiments may comprise one or more clips 25 and one or more elastically deformable couplings 42, 43. For example, a

comfort liner 20 may comprise two front clips 25 and two rear elastically deformable couplings 43. Other embodiments may comprise two front clips 25, two front elastically deformable couplings 42, and two rear elastically deformable couplings 43. Still other embodiments may comprise two rear clips 25 and two front elastically deformable couplings 42. Other embodiments may comprise any combination thereof.

Also contemplated in this disclosure is a comfort liner 50 comprising a four-way stretch fabric 52 coupling a neck roll 51 of the comfort liner 50 the main body of the comfort liner 50. FIG. 7 depicts a bottom view of a comfort liner 50 comprising a four-way stretch fabric 52 coupling a neck roll 51 to the comfort liner 50. Such a configuration provides more free movement of the comfort liner 50 against the low friction layer 30 described above. In some embodiments, the neck roll 51 is directly and removably coupled to either the low friction layer 30 or the protective shell 10 with elastically deformable couplings 43 or clips 25, as described above. In other embodiments, the neck roll 51 is not directly coupled to either the protective shell 10 or the low friction layer 30.

It will be understood that implementations are not limited to the specific components disclosed herein, as virtually any components consistent with the intended operation of a method and/or system implementation for helmets may be utilized. Accordingly, for example, although particular protective shells and comfort liners may be disclosed, such components may comprise any shape, size, style, type, model, version, class, grade, measurement, concentration, material, weight, quantity, and/or the like consistent with the intended operation of a method and/or system implementation for a helmet may be used.

In places where the description above refers to particular implementations of helmets, it should be readily apparent that a number of modifications may be made without departing from the spirit thereof and that these implementations may be applied to other helmets. The accompanying claims are intended to cover such modifications as would fall within the true spirit and scope of the disclosure set forth in this document. The presently disclosed implementations are, therefore, to be considered in all respects as illustrative and not restrictive, the scope of the disclosure being indicated by the appended claims rather than the foregoing description. All changes that come within the meaning of and range of equivalency of the claims are intended to be embraced therein.

The invention claimed is:

1. A football helmet comprising:
an outer shell having an inner surface;
an energy absorbing layer having an inner surface and an outer portion, the outer portion of the energy absorbing layer being positioned adjacent to the inner surface of the outer shell;
a plastic layer positioned adjacent to and underlying a majority of the inner surface of the energy absorbing layer, the plastic layer having an opening formed therethrough;
a comfort liner assembly having an outer surface, a foam layer, and a coupling member that extends from said outer surface, wherein the coupling member has: (i) a base portion adjacent to said outer surface, (ii) an intermediate portion with a first width, and (iii) an end portion with a second width that is greater than the first width of the intermediate portion; and

wherein the comfort liner is removably secured to the plastic layer by inserting the coupling member through said opening in the plastic layer whereby said end portion of the coupling member (i) extends past the plastic layer, and (ii) is positioned within an extent of the energy absorbing layer.

2. The football helmet of claim 1, wherein the plastic layer has an outer periphery and the energy absorbing layer has an outer periphery, and wherein the outer periphery of the plastic layer is less than the outer periphery of the energy absorbing layer whereby at least an extent of the outer periphery of the energy absorbing layer is exposed.

3. The football helmet of claim 1, wherein (a) the inner surface of the energy absorbing layer defines an interface area, and (b) an outer surface of the plastic layer defines an interface area, and

wherein the interface area of the plastic layer is less than the interface area of the energy absorbing layer.

4. The football helmet of claim 1, wherein the comfort liner includes a main body portion and a strap, wherein said strap extends between the main body portion and an inner surface of a brow region of the outer shell.

5. The football helmet of claim 4, wherein the energy absorbing layer has a lower edge that is positioned in the brow region, and wherein the strap includes an attachment device to releasably couple the strap to an extent of the lower edge the brow region.

6. The football helmet of claim 5, wherein the attachment device is an elongated clip configured to be retained within a receiver formed in the energy absorbing layer in the brow region of the outer shell.

7. The football helmet of claim 1, wherein the outer shell is formed from a thermoplastic polymer.

8. The football helmet of claim 7, wherein the plastic layer has a thickness in at least one region that is less than 3 mm.

9. The football helmet of claim 7, wherein the thermoplastic polymer is polyethylene terephthalate.

10. The football helmet of claim 1, wherein a lower edge of energy absorbing layer is substantially aligned with an extent of a lower edge of the plastic layer.

11. The football helmet of claim 1, wherein the comfort liner has a monolithic construction.

12. The football helmet of claim 1, wherein the coupling member is elastically deformable and configured to facilitate relative movement between the comfort liner and the plastic layer.

13. The football helmet of claim 1, wherein the energy absorbing layer is comprised of a plurality of individual layers.

14. A football helmet comprising:
an outer shell having an inner surface and a brow region;
an energy absorbing layer having an inner surface and an outer portion, the outer portion of the energy absorbing layer being connected to the inner surface of the outer shell;

a plastic layer coupled to and underlying a majority of the inner surface of the energy absorbing layer;
a comfort liner assembly configured to be positioned between the plastic layer and a head of a wearer when the football helmet is worn by the wearer, the comfort liner assembly including a foam layer and a coupler that outwardly extends from an outer surface of the comfort liner assembly;

wherein the comfort liner is removably secured to the plastic layer by inserting the coupler through an opening in the plastic layer to define an installed position; and

11

wherein in the installed position, an end portion of the coupler extends past the plastic layer and resides within an extent of the energy absorbing layer, and an intermediate portion of the coupler resides within the opening formed in the plastic layer.

15. The football helmet of claim **14**, wherein the intermediate portion of the coupler has a first width, and the coupler further includes a base portion that: (a) is positioned adjacent to the outer surface of the comfort liner, (b) is positioned between the outer surface of the comfort liner and the intermediate portion, and (c) has a second width that is greater than the first width.

16. The football helmet of claim **15**, wherein the coupler further includes an end portion that: (a) extends outwardly from the intermediate portion, and (b) has a third width that is greater than the first width.

17. The football helmet of claim **15**, wherein the coupler is not integrally formed with the comfort liner.

12

18. The football helmet of claim **14**, wherein the plastic layer includes at least one projection that extends from an outer surface of the plastic layer and is positioned within the energy absorbing layer.

19. The football helmet of claim **14**, wherein the plastic layer has an outer periphery and the energy absorbing layer has an outer periphery, and wherein the outer periphery of the plastic layer is less than the outer periphery of the energy absorbing layer whereby at least an extent of the outer periphery of the energy absorbing layer is exposed.

20. The football helmet of claim **14**, wherein (a) the inner surface of the energy absorbing layer defines an interface area, and (b) an outer surface of the plastic layer defines an interface area, and

wherein the interface area of the plastic layer is less than the interface area of the energy absorbing layer.

21. The football helmet of claim **14**, wherein a lower edge of energy absorbing layer is substantially aligned with a majority of a lower edge of the plastic layer.
